UNITED STATES PATENT OFFICE

2,485,068

BRUSH COVER

Alfred H. Santana, Baltimore, Md.

Application June 30, 1947, Serial No. 758,089

3 Claims. (Cl. 206—15.1)

1

This invention relates to a brush cover and has for its primary object to retain the bristles of a paint brush or the like in the best possible condition during shipment and handling.

Another object is to preserve the bristles in condition for reuse after the brush once has been put into service.

A further object is to exclude access or movement of air around the bristles and hence prevent the bristles from becoming stiff after the brush has once been used.

The above and other objects may be attained by employing this invention which embodies among its features an air tight pliable sheath of elastic material adapted to encircle the bristles of a brush, a reduced neck at one end of the sheath for encircling the handle of the brush, a skirt at the end of the sheath opposite the neck, said skirt being adapted to be folded back to overlie one side of the sheath and completely enclose the ends of the brush bristles remote from the handle.

Other features include an extension on the neck adapted to be folded back upon itself to enclose the end of the skirt when the latter is in folded position and an inwardly extending reinforcing and stiffening bead at the junction of the sheath and the skirt.

In the drawings Figure 1 is a perspective view of a sheath embodying the features of this invention illustrating in broken lines a brush in position therein,

Figure 2 is an edge view of Figure 1,

Figure 3 is a view similar to Figure 1 showing the skirt folded back over the ends of the bristles remote from the handle of the brush and with its folded end encompassed in an extension on the neck of the sheath,

Figure 4 is a top plan view of the cover,

Figure 5 is a vertical sectional view taken substantially along the line 5—5 of Figure 2,

Figure 6 is a vertical sectional view taken substantially along the line 6—6 of Figure 1, and

Figure 7 is a vertical sectional view taken substantially along the line 7—7 of Figure 3.

Referring to the drawings in detail my improved brush cover designated generally 10 comprises a sheath 11 having formed at one end a reduced neck portion 12. A skirt 13 is formed integrally with the end of the sheath 11 opposite the neck portion 12, and the end of the skirt is preferably slightly contracted as at 14 for a purpose to be more fully hereinafter explained.

Formed on the neck 12 is an elongated extension 15 which terminates in a reinforcing bead

2

16, and extending inwardly from the sheath adjacent its junction with the skirt is a reinforcing and stiffening bead 17 which as illustrated in Figures 5 through 7 is adapted to engage the bristles of a paint brush adjacent the ends remote from the brush handle.

In use a paint brush designated generally 18 comprising a handle 19 a brush head 20 and bristles 21 is slipped into the sheath as illustrated in the drawings. It will be understood, of course, that the sheath 11 is shaped to conform to the shape of the brush head and is preferably formed from an airtight, pliable elastic material such as rubber. The brush handle is introduced into the sheath through the constricted end 14 of the skirt 13 with the handle 19 extending through the neck 12 and extension 15 thereof. When in this position the bead 17 will encompass the bristles 21 of the brush adjacent their ends remote from the head 20. The skirt 13 is then folded upwardly to overlie one face of the sheath 11 as illustrated in Figures 3 and 7, and the constricted end 14 of the skirt 13 overlies the neck portion 12 of the sheath 11. The extension 15 is then rolled down upon itself with the constricted portion 14 as suggested in Figure 3 so as to wholly enclose the bristles 21 of the brush 18 and exclude air, dust and dirt therefrom.

In the event that the device is applied to new brushes it is obvious that they may be handled and transported without danger of collecting dust and dirt in the bristles and the bristles themselves will be protected from injury. Also, by reason of the fact that the cover is formed of an air tight substance it is obvious that even though the brush may have been used, the soft pliable condition of the bristles may be preserved due to the fact that air is excluded therefrom and hence evaporation of any paint vehicle adhering to the bristles will be prevented. In this way the brush even though it may have once been used may be preserved for an indefinite period without requiring that it be cleaned, and even after long periods of storage with paint contained in the brush, the bristles thereof will remain soft and pliable and ready for use.

While in the foregoing there has been shown and described the preferred embodiment of this invention it is to be understood that minor changes in the details of construction, combination and arrangement of parts may be resorted to without departing from the spirit and scope of the invention as claimed.

What is claimed is:

1. A brush cover comprising a sheath of air-

tight pliable elastic material adapted to encircle the bristles of a brush, a reduced neck at one end of the sheath for encircling the handle of the brush and a skirt at the end of the sheath opposite the neck, said skirt being adapted to be folded back to overlie one side of the sheath and completely enclose the ends of the brush bristles remote from the handle and an inwardly extending stiffening and reinforcing bead at the junction of the sheath and the skirt.

2. A brush cover comprising a sheath of air-tight pliable elastic material adapted to encircle the bristles of a brush, a reduced neck at one end of the sheath for encircling the handle of the brush and a skirt at the end of the sheath opposite the neck, said skirt being adapted to be folded back to overlie one side of the sheath and the neck completely to enclose the ends of the brush bristles remote from the handle and an extension on the neck adapted to be folded back upon itself to enclose the end of the skirt when the latter is in folded position and an inwardly extending reinforcing and stiffening bead at the junction of the sheath and the skirt.

3. A brush cover comprising a sheath of air-tight pliable elastic material adapted to encircle the bristles of a brush, a reduced neck at one end of the sheath for encircling the handle of

the brush and a skirt at the end of the sheath opposite the neck, said skirt being adapted to be folded back to overlie one side of the sheath and the neck completely to enclose the ends of the brush bristles remote from the handle and an extension on the neck adapted to be folded back upon itself to enclose the end of the skirt when the latter is in folded position and an inwardly extending reinforcing and stiffening bead at the junction of the sheath and the skirt and a reinforcing bead at the free end of the extension of the neck.

ALFRED H. SANTANA.
